J. F. HEARN

ELECTRIC CURRENT CONTROLLING DEVICE

Filed Nov. 28, 1919

Inventor:
John F. Hearn.

by *Jul Ch. Palmer* At't'y.

UNITED STATES PATENT OFFICE.

JOHN F. HEARN, OF PASSAIC, NEW JERSEY, ASSIGNOR TO WESTERN ELECTRIC COMPANY, INCORPORATED, OF NEW YORK, N. Y., A CORPORATION OF NEW YORK.

ELECTRIC-CURRENT-CONTROLLING DEVICE.

Application filed November 28, 1919. Serial No. 341,151.

To all whom it may concern:

Be it known that I, JOHN F. HEARN, a citizen of the United States, residing at Passaic, in the county of Passaic, State of New Jersey, have invented certain new and useful Improvements in Electric-Current-Controlling Devices, of which the following is a full, clear, concise, and exact description.

This invention relates generally to electric circuit controlling devices, and more particularly to selective switches for use in automatic systems.

The invention has for its object to provide a switch of the automatic selective type in which the weight of the moving part shall be compensated.

In its preferred embodiment the invention is applied in the form of a selector switch to an automatic telephone system. The selector switch has movable brush rods carrying brushes arranged to wipe over a commutator plate, and wipers arranged to engage contacts of a terminal bank by means of which, connections may be established. Friction rollers are provided to impart motion to the brush carrying rods. The number of brushes and wipers carried by the rod has usually been about five. It will be seen that if the same rod and rollers are used to carry a greater number of brushes and wipers, say fifteen or more, the tendency is for the friction roller to slip unless this additional weight is compensated for in some manner. This invention provides a means for compensating for this weight. The particular compensating means disclosed possesses advantages in that it is compact, simple and has a negligible mass in its moving parts.

The drawing illustrates an embodiment of the present invention.

In the drawing, the rod 1, supported by and sliding in guides in the frame plates 17 and 32 carries the brush 3 which is adapted to contact with the contacts on the commutator bank 5. Rod 1 also carries the wipers 2, which contact with the terminals in banks 4. At the lower end of rod 1 is attached a flat stiff metal strip 6 passing between the constantly rotating friction rollers 7 and 9 and the rollers 16 and 15. Rollers 7 and 9 revolve on the shafts 8 and 10 respectively in the directions indicated by the arrows.

Rollers 16 and 15 revolve freely on the shafts 33 and 34.

The shaft 33 is supported by the bell crank 13, which is hinged on the pin 35. The other end of the bell crank 13 extends in front of the pole pieces of electromagnet 11 and is adapted to be drawn up against the magnet, thereby forcing the roller 16 against the strip 6. The pressure of the roller 16 against the strip 6 pushes the strip 6 against the friction roller 7 and an upward motion in the rod 1 is thereby produced.

Similarly a downward motion is produced by the roller 9, when the electromagnet 12 draws the arm of the bell crank 14 upward. The crank 14 hinged on the pin 36 forces the roller 15 to engage the strip 6 with the roller 9.

The frame 25 is fastened by means of screws 28 to a portion of the main framework 27. Attached to the frame 25, by means of an adjusting bolt 29 having the nut 30 and lock nut 31, is a coil spring 26. A flexible ribbon 24 is attached at one end to the spring 26 and is wound about the spiral drum 23 and fastened to it by the screw 37. Drum 23 is adapted to revolve about the shaft 22 supported by the frame 25. Circular pulley 20 also revolves on shaft 22 and is fastened to the drum 23 so as to revolve therewith. A second ribbon 19 is fastened at one end by screw 21 to the circumference of the pulley 20 and adapted to wind thereon. The other end of the ribbon 19 is attached by means of a clamp 18 to the brush carrying rod 1.

The tension in the spring 26 varies directly with its extension. It may be adjusted by means of the bolt 29 and the adjusting nut 30 and lock nut 31.

The spiral drum 23 is made of such a form that its radius at the point of tangency varies inversely with the extension of the spring 26. It will be seen that the force exerted at the circumference of the pulley 20 and in the ribbon 19 is therefore constant and equal for all positions of the rod 1.

What is claimed is:

1. In a circuit controlling device, the combination of a movable circuit controlling member, means for varying the position thereof, and means to exert a uniform force

on said circuit controlling member to compensate for its weight, whereby said circuit controlling member is adapted to remain in its adjusted position.

5. 2. In a circuit controlling device, the combination of a movable circuit controlling member; means for varying the position thereof, and retractile spring means to uni-

formly compensate for the weight of said circuit controlling member in all positions ¹⁰ thereof.

In witness whereof, I hereunto subscribe my name this 25th day of November, A. D., 1919.

JOHN F. HEARN.
